UNITED STATES PATENT OFFICE.

JAMES TAYLOR, OF HORWICH JUNCTION, NEAR BOLTON, ENGLAND, ASSIGNOR TO
MATHER & PLATT LIMITED, OF MANCHESTER, ENGLAND.

APPLIANCE FOR HUMIDIFYING WARPS.

1,267,822.

Specification of Letters Patent. Patented May 28, 1918.

Application filed July 18, 1914. Serial No. 851,700.

To all whom it may concern:

Be it known that I, JAMES TAYLOR, a subject of the King of Great Britain and Ireland, and a resident of Horwich Junction, 5 near Bolton, in the county of Lancaster, England, have invented certain new and useful Appliances for Humidifying Warps, of which the following is a specification.

This invention relates to improvements 10 in appliances for imparting moisture to warps in looms or to other yarns or equivalents or to rovings slivers or the like in process of formation or utilization in any textile machinery. The improvements are particularly applicable to the treatment with water 15 of warps in looms, in connection with which treatment it will be hereinafter fully described. From such description its application to the treatment of other yarns or 20 fibrous strands in other machinery will be understood as will also the application of liquids or solutions other than water.

The warps in looms on their way to the healds have before now been treated by 25 being wiped with a wet or moist wick or the like. In carrying out my improvements the warps are similarly wiped.

With the appliances previously in use or suggested the water has been contained in 30 a free condition in a trough, tube or the like which has extended across the loom near to the warps. From such a trough, tube, or the like the water was led to the warps by a wick or the like. With such an arrangement and water supply heavy and 35 cumbrous appliances were used, a large quantity of water was in use at a time and was liable to stink, and the water supply to the warps could not easily be maintained at 40 a constant rate unless the supply was harmfully copious.

According to my invention there is no free water or bulk of water in the tube or equivalent which extends across the loom 45 and is provided with a wick or equivalent to wipe the warps. The water is contained in small bulk in a tank which is on the side or frame of the loom. The tube or the like which extends across the loom contains 50 fibrous or like material to any required and suitable extent and communication between such fibrous material and the water tank is made in such a way that the material is only maintained in a damp condition, and there 55 is no free water in the tube. This damp material communicates its moisture to the wick

or external fibrous covering of the tube which conveys the moisture to the warps. The supply of liquid from the tank to the fibrous filling or the like contained in the 60 tube can be very easily controlled, the amount communicated to the warps can be regulated as desired, and there is no danger of a too copious supply of water reaching the warps.

Moisture imparted to the warps in the manner of this invention strengthens them where additional strength is required and the projecting fine fibers of the warps are smoothly laid down and back on the warps 70 to the great improvement of the weaving.

The accompanying drawings represent apparatus which can be conveniently used in a loom according to this invention and will now be described.

Figure 1 represents a back view of a loom with one form of my improved appliances thereon.

Fig. 2 shows the same parts in vertical cross section.

Fig. 3 shows in greater detail and to a larger scale the damping appliance of Figs. 1 and 2.

Fig. 4 shows the appliances of Fig. 3 in vertical cross section.

Fig. 5 shows in vertical section a "drip" feed device for supplying water to the damping appliance. Such "drip" feed device is well-known in connection with the supply of lubricants. In this figure the feed device is shown in its feeding or open position.

Fig. 6 shows the "drip" feed device closed.

Fig. 7 is a view partly in vertical section of another form of liquid feed device.

Fig. 8 shows part of this last feed device 95 in plan.

Fig. 9 is a vertical cross sectional view of another form and disposition of appliance for damping the warps.

Similar letters of reference are used to 100 indicate similar parts where they occur in the different drawings.

A is the frame of the loom, B the warp beam, C the warps, D the back rest, and E the healds.

F is a light thin walled perforated zinc or other suitable tubular member covered with absorbent flannel or felt G. The tubular member and the felt are clamped in a carrier H and this carrier is borne by arms 110 J which are hinged in brackets K attached to the bolts or screws by which the back

rest D is secured in place in the loom frame. With an appliance formed and mounted as described the tubular member F falls by its own weight with its covering G upon the upper surface of the sheet of warps just below the back rest. See Fig. 4. The interior of the tube F contains absorbent textile material in the form of loosely spun or stranded unsized cotton cords L longitudinally disposed. At one end the tube F is attached to a length of indiarubber pipe M. The indiarubber pipe leads to and is held in a closed water tank N suitably fixed on the loom frame. The strands L pass through the indiarubber pipe and their ends dip into the water contained in the tank. The strands L suck up water from the tank, become wet throughout their lengths from end to end of the tube F, and through the perforations in such tube transmit water to and thus also wet the flannel or felt covering G. This in turn, when the apparatus is in action, wets to the required extent the warps which pass under and in contact with it.

The degree or amount of moisture supplied to the covering G may be varied by varying the number of ends of strands L which dip into the water. By immersing the ends of all of them a maximum moisture supply is insured; by lifting and keeping any desired number of them out of the liquid the liquid supply can be reduced as desired.

Other water supplying devices than that just described may be employed for delivering moisture to the strands or other absorbent substance contained within the tube F. For example the indiarubber pipe M which communicates with the interior of the tube F may be led upward to a higher tank N which is furnished with the "drip" feed device O. See Figs. 5 and 6. The "drip" device supplies water to the interior of the tube M where it is brought into contact with the ends of the strands of absorbent material within the tube F, which strands serve to carry the moisture throughout the length of the tube. The construction of this "drip" feed device is known; it is illustrated in the drawings, and needs no further description.

The capillary conduction or feed of water along the length of the damping appliance by means of an absorbent lining, filling or packing contained therein as indicated in our British provisional specification 16873/13 is of great value in attaining uniformity of result in the loom, no matter what mode of liquid supply to the lining, filling, or the like may be adopted, and is still more of value when the capillary feed or conduction of liquid along the damping appliance is conjoined with a capillary means of supply from the water tank as shown in Fig. 3.

Figs. 7 and 8 illustrate a form of water supply device for use with absorbent strands which dip into the water. P is a water tank, consisting of a closed vessel having a single outlet from which the pipe Q projects. R is a small tray placed below the lower end of the pipe Q. With the parts in the position shown in Fig. 7 and with the tank P full of water, water will run out into the tray R until it reaches a level therein which closes the lower end of the pipe. Preferably the lower end of this pipe is not cut at right angles to its axis. See Fig. 7. The tray R is of small capacity and there is thus very little water exposed to the atmosphere at any time and the danger of the water stinking or becoming foul is very much reduced. R¹ is a tray upon which any strands L which are not to be in the water are laid. R² is a clip to hold the end of the tube M.

In the arrangement shown in Figs. 1, 3 and 4 a shaft which carries one of the arms J also has attached to it an arm S. This latter arm is suitably connected to the starting handle, the brake or to other suitable part of the loom, so that as the loom is stopped the tube F and its covering are lifted out of contact with the warps, and are again lowered into contact therewith when the loom starts.

With the feed strands L shown in Figs. 3, 7 and 8 the supply must not be copious enough to cause drops to fall from the cover G, even when the damping appliance is raised out of contact with the warps. The indiarubber tube M permits the damping appliance to have its required movement to and from the warps. If desired, however, the tube M with its contained strands may be removed from its water tank when the loom is to make a prolonged stop.

A still further modification is shown in Fig. 9. Here the damping appliance of the previous figures is not employed to directly apply moisture to the warps. It applies its moisture to a roller T in contact with which the warps pass. This roller can be of glass or of non-corrodible metal, and may be rotated in the direction of the curved arrow, that is in a direction opposite to the direction of travel of the warps. Such a roller does not require to be moved out of contact with the warps when the loom is stopped.

For the purpose of getting the very best weaving effect in a loom a weak solution of soft soap may be used.

The improved method of applying moisture to yarns dispenses with the necessity of humidifying the atmosphere of the sheds and work rooms, and permits varying degrees of moisture to be imparted to the yarns of various machines in one room.

The improved appliances enable the operative to vary the extent or degree of mois-

ture or dampness imparted to the yarns as desired.

Instead of a single damping appliance as described, two or more may be used, as, for example, on opposite sides of the warps.

The damping appliances hereinbefore described have only been supplied with liquid from one end, but if desired, and particularly for use with broad looms, liquid may 10 be supplied from and to both ends of the damping appliance.

What I claim is:—

Apparatus for damping warps in a weaving loom comprising a hollow holder extending across the machine in proximity to the warps, capillary absorbent material in said holder, a covering for said holder of capillary absorbent material, perforations in the 15

wall of said holder for permitting the liquid in the absorbent material in said holder to 20 be transferred to the absorbent covering, a source of liquid separate from said holder, means for feeding the liquid from said source to said material in said holder also comprising capillary absorbent material, and 25 means for regulating the supply of liquid fed from said source to said capillary and absorbent material comprised within said feeding means.

In witness whereof I have hereunto set 30 my hand in the presence of two subscribing witnesses.

JAMES TAYLOR.
